PHOTOCHEMICAL EXPLORATION METHOD

Robert O. Smith, Fort Worth, Tex.

No Drawing. Application July 10, 1940,
Serial No. 344,736

8 Claims. (Cl. 23—230)

This invention relates to a method of geophysical prospecting for hidden petroleum deposits by the detection and subsequent correlation of evidences of concentrations of petroleum derived constituents, such as saline products, and it has particular reference to a method embracing the systematic collection of a series of samples of soil at or near the earth's surface along predetermined reconnaissance surveys, preserving the said samples in containers impervious to air and moisture, and subjecting the same to laboratory procedure calculated to disclose data which may be tabulated and subsequently correlated to produce a definitely outlined area or closure within which the production of petroleum may reasonably be expected.

The primary object of the invention resides in the provision of a method of geophysical exploration whereby the perimeter of an anomaly may become apparent at the earth's surface so that, when a map of the area under examination has been prepared, an outline of, or "halo" above the productive area can be definitely fixed, enabling the operator to determine where petroleum production is most likely to occur and to afford a reliable means of establishing a favorable drilling location.

Among the petroleum derived constituents known to be indicators of hidden petroleum deposits are saline products which are considered very important and the present invention deals primarily with such indicators and particularly with alkaline salts (NaCl, KCl, etc.) which are known to migrate to the earth's surface in varying quantities from subterranean petrolierous deposits and are found in definite concentrations at points at the surface above the edges of salt domes, and similar structures.

It is of general knowledge that saline constituents of the soil are more or less constant throughout the earth's surface and random examinations of soil samples offer no assurance of the emanation of such derivatives from a petrolierous source, but where samples are consistently taken at definitely spaced intervals over a certain area, and concentrations of the products appear evident from consistent correlation, it may well be supposed that a petroleum bearing anomaly exists therebelow.

Leakage products from petroleum deposits also consist of several types of hydrocarbons, primarily methane, and other gaseous products, which I have also considered as evidenced by my previous applications, as for example Serial No. 280,431, filed June 22, 1939; Serial No. 298,449, 55

filed October 7, 1939, and the herein described method is a variation of the methods described in the said applications. Since the known derivatives of petrolierous deposits include alkaline salts, therefore, it is the object of the instant invention to provide a means whereby such products can be quantitatively measured, indicated by a curve upon an ordinated chart, properly correlated and finally outlined, on a map of the area, a closure within which production may reasonably be expected.

While there are several methods of laboratory procedure I employ, I prefer to place about two (2) grams of each sample in a container, preferably a tube of conventional size, and add enough pure distilled water thereto to thoroughly immerse the soil. The tube is shaken or agitated sufficiently to cause the soil to be thoroughly suspended in the water. The soil is then allowed to settle in the tube and until the alkaline salt (NaCl, KCl) content of the sample has been wholly dissolved in water.

After sufficient agitation and settling of the soil sample has been accomplished to effect the thorough dissolution of the alkaline salt content of the sample in the water, the solution is decanted from the soil and a quantity thereof (approximately 10 c. c.) is deposited in another tube to which is added about five (5) drops of a ten (10%) percent solution of silver nitrate (AgNO₃) whereupon the mixture is subjected to ultra-violet rays, preferably sunlight, for a period of approximately ten (10) minutes. Longer periods of exposure may be resorted to depending upon the conditions under which the exposure is made, but all of the said samples must be exposed for the same period of time for proper and uniform results.

The length of the period of exposure depends largely upon the angle of the rays, if the sample is subjected to sunlight, since the rays early in the morning or late in the afternoon are projected at a more acute angle and require longer exposure to obtain the proper results. A more uniform period of exposure can be accomplished, of course, by the application of artificial rays, which is sometimes practicable and desirable, in the absence of natural ultra-violet rays from the sun, but such application is not always conveniently accessible nor as effective.

At the end of the exposure period, if all of the samples, each being deposited in separate tubes, have been uniformly exposed, the solutions will appear in various hues and shades of yellow, orange, red, purple and dark purple, as progres-

sions from the original pure crystal clear water to an almost black color, the latter reflecting the largest quantity of alkaline salts (NaCl) present in the sample, while the hues of yellow, orange, red and purple, respectively, reflect the respective relative quantities of the product present in each sample, which may be tabulated accordingly. The variation of tints reflect the variation in quantity, usually expressed in parts per million, of the product present in each sample.

Palpably, in the application of the method heretofore described the densest tints or darkest colors reflect the greater concentrations of the product (NaCl) while the lighter hues and variations of color reflect the lesser quantities of the product present in the samples and are recorded accordingly on the chart. For example, the hues which manifest themselves during a predetermined period of exposure, such as yellow, orange, red, purple, and dark purple, are given quantitative values according to their variation of density, based upon parts per million, and are recorded along the ordinate of a chart while the sample stations are designated along the abscissa thereof and the curve, commonly referred to as the "mineral" curve, interpretatively records the results of the investigation, and the peaks and recessions of the curve will enable the interpreter to outline the definite productive structure on the map of the area.

After an observation of the general geological pattern of the area has indicated a salt dome structure, a radial survey is made which consists of several reconnaissance lines radiating from a common point, along each of which a series of samples are taken, properly identified by station number and survey, and transmitted to the laboratory. A curve is then made from the laboratory findings for each reconnaissance line, and these several lines are afterwards correlated with each other to establish the outline or perimeter of the closure under consideration and such closure is outlined upon the map of the area.

The curves, as stated, reflect pronounced peaks and recessions along each survey, the peaks, when found to be more or less pronounced and consistent, indicating the greater concentrations of the products sought, and thus clearly indicate the outline of the structure, when properly correlated with other surveys, so that the outline or "halo" may be readily depicted upon the map of the area.

A quantitative value may be arbitrarily adopted for each color or tint, according to the individual requirement, it being necessary only to determine the points of greatest concentration of the product along the survey and to be able to accurately and definitely fix these concentrations upon correlation of the several surveys of the area. Only a quantitative determination of the relative content of the product (alkaline salts) of each soil sample taken over any given survey is necessary to be considered and it is not required that an exact quantitative measurement of the product be had so long as the peaks and recessions appearing on the chart are sufficiently pronounced to enable the interpreter to point with reasonable certainty to a definite outline of the structure under examination.

The reaction of the alkaline salts products, when contacted by the silver nitrate solution, strongly resembles the reaction which is manifest in photochemistry and for this reason I prefer to refer to my method as a photochemical process. The procedure herein described may be

modified, particularly with respect to the length of time the various samples are exposed to ultra-violet rays, since the longer each sample is exposed the darker the color it assumes, and continuous exposure would result in coloring each sample a dark purple which, in appearance, would be almost black. It is highly essential, therefore, that all of the samples be exposed for a uniform period of time, regardless of the period of exposure decided upon. It has been stated that a period of ten (10) minutes is deemed to be a sufficient length of time to obtain the best results. However, it is obvious that greater periods of exposure may be adopted, if desired, with equally responsive results although each sample may be shades darker, necessitating the establishment of a different quantitative valuation for basic consideration.

In accomplishing other than radial surveys, heretofore referred to, such structures as faults, and the like, may be detected by laying out a series of reconnaissance surveys in parallel relationship, which may be referred to as a grid survey, so that when the resultant curve is correlated in each instance the excessive peaks thereof, indicating the concentrations of the product, will point to a definite structure which may extend along a course simulating a fault, or other similar structure, and coupled with surface geology may indicate a valuable anomaly.

Manifestly, the method herein described may be modified by persons skilled in geophysical and geochemical sciences in the course of experimental and practical application and such modifications as may be resorted to from time to time and which may be considered as falling within the spirit and intent of the method as herein outlined may also be considered as falling within the scope of the appended claims.

What is claimed is:

1. In the art of geophysical exploration for hydrocarbon deposits, the method of detecting concentrations of hydrocarbons over buried deposits by the determination of the saline products in the soil comprising systematically selecting soil samples over the area, dissolving out the alkaline content of the said samples in pure water, adding a silver nitrate solution to the said alkaline solution, subjecting the mixture to ultra-violet rays for a predetermined period and measuring the hydrocarbon content by resultant color and tint variations.

2. In the art of geochemical exploration for hydrocarbon deposits, the method of determining the alkaline content of the soil overlying suspected petroleum deposits by systematically collecting soil samples over a predetermined course, dissolving the alkaline salt content of each sample in pure water, adding a quantity of a silver nitrate solution to the said alkaline solution, subjecting the resultant mixture to light rays for a predetermined period and establishing the hydrocarbon content of each sample by the resultant color and tint variations.

3. The method of locating hidden hydrocarbon deposits through the quantitative determination of alkaline properties of the soil overlying a suspected petroleum deposit which consists in collecting samples of soil overlying the said deposits, immersing a quantity of each sample in pure water to dissolve out the alkaline salt content thereof, decanting the solution and adding thereto a quantity of silver nitrate solution, subjecting the mixture to light rays and measuring the

hydrocarbon content of each sample by the resultant color and tint variations.

4. The herein described method of locating hidden hydrocarbon deposits by the determination of the alkaline contents of the soil thereover which consists in selecting samples of the said soil systematically over the area under investigation, dissolving the alkaline salts from each sample in pure water, mixing a quantity of the solution with a quantity of a silver nitrate solution, subjecting the mixture from each sample to ultra-violet rays for a predetermined period and measuring the hydrocarbon content of each sample by resultant color and tint variations of the said mixture.

5. The herein described method of detecting petroleum deposits by concentrations of petroleum derived hydrocarbons indicated by the concentrations of alkaline properties in the soil above the said deposits at the surface which consists in selecting samples of soil at predetermined intervals along a fixed course, dissolving the alkaline salt content from each sample in pure water, adding a solution of silver nitrate to the said alkaline salt solution, subjecting the mixture from each sample to light rays for a predetermined period, measuring the hydrocarbon content of each sample by the resultant color and tint variations and indicating the said measurements with respect to the original location of the said sample.

6. In the art of exploration for petroleum deposits by geochemical investigation to determine the alkaline contents of the overlying soil which consists in systematically selecting a series of soil samples along a predetermined course, dissolv-

ing the alkaline salts from each sample in pure water, decanting the solution, adding a quantity of a solution of silver nitrate to the alkaline salt solution from each sample, exposing the combination to ultra-violet rays for a predetermined period and measuring the hydrocarbon content of each sample by the color and tint variations thereof resulting from said exposure.

7. In the art of geochemical exploration for hydrocarbon deposits in the earth, the method of detecting concentrations of surface hydrocarbons indicated by the concentration of saline products of the soil above the suspected deposits which consists in systematically selecting a series 15 of soil samples over the area under consideration, dissolving the alkaline salts from each sample in pure water, adding a fixed quantity of a silver nitrate solution to the alkaline salts solution from each sample, subjecting the same to ultra-violet rays and measuring the hydrocarbon content of each sample by the resultant color and tint variations.

8. In the art of exploration for buried hydrocarbon deposits by detecting the surface hydrocarbon concentrations of the soil thereabove indicated by the saline concentrations of the said soil consisting in systematically selecting a series 25 of soil samples, immersing each of the said samples in pure water to dissolve out the alkaline salt content thereof, decanting the solution and adding thereto a quantity of a solution of silver nitrate, subjecting the mixture to ultra-violet rays for a specified period and measuring the hydrocarbon content of each sample by the resultant variations in color and tint thereof.

ROBERT O. SMITH.
